UNITED STATES PATENT OFFICE.

ANALDO M. ENGLISH, OF BOSTON, MASSACHUSETTS, ASSIGNOR TO GEORGE BECKER, OF NEW YORK, N. Y.

MACHINE FOR THE MANUFACTURE OF PLAITED BRAID.

SPECIFICATION forming part of Letters Patent No. 433,075, dated July 29, 1890.

Application filed January 21, 1890. Serial No. 337,583. (No model.)

To all whom it may concern:

Be it known that I, ANALDO M. ENGLISH, of Boston, county of Suffolk, State of Massachusetts, have invented an Improvement in Machines for the Manufacture of Plaited Braid, of which the following description, in connection with the accompanying drawings, is a specification, like letters on the drawings representing like parts.

5 This invention has for its object to provide a machine for the production of a plaited braid from flat or round strands.

10 My machine has strand-carriers, herein shown as needles, which are actuated in succession and after a novel manner. The braid produced may be of various forms in cross-section, such as quadrangular, triangular, or of other many-sided forms.

15 In accordance with my invention a series 20 of strand-carriers, preferably hollow needles, are attached to holders, preferably removably attached to radially-moving carriages, so that the strands, whether flat or round, are, in the reciprocation of the strand-carriers past a 25 common center, made to cross each other, each carrier entering a loop or stitch in a strand of some other carrier and having its own loop or stitch entered in turn by another carrier, as will be hereinafter described.

30 The plaited braid produced by the machine herein to be described is herein represented as quadrangular in cross-section and requires four flat strands for its production, two of the strands being shown as narrower than the

35 other two; but if the machine should contain but three strand-carriers the braid produced might be triangular, and with more than four strand-carriers the braid may be oblong.

40 Each strand-carrier, as herein shown, has a spring-finger, which acts to support the strand between the point of the strand-carrier and the holder as the point of the strand-carrier passes the center line of the machine or the point occupied by the mandrel or core, the 45 said spring supporting one side of the strand or braid, while another strand-carrier enters the space between the strand-carrier and spring to thus enter a loop or stitch. A "loop" or "stitch," as I may call it, is made in each 50 strand, and each loop or stitch is entered and

locked by a loop of another strand, each loop locking the other, as will be shown and described.

Figure 1 is a top or plan view of the main parts of a machine embodying my invention, 55 the support for the mandrel or core and the spool-supports being also omitted, a part of the bed and one of the carriages at the right being broken off to save space on the drawings, the parts so omitted being just the same 60 as the parts shown in full at the left. Fig. 2 is an enlarged section in the line $x-x$ of Fig. 1, looking to the right. Fig. 3 is a section in the line $x'-x'$ of Fig. 1. Fig. 4 is a detail in section, chiefly to show the clamping mechanism for clamping the strand at certain times in the production of the plait. Fig. 5 is a detail showing the end of one of the guides or ways. Fig. 6 is a detail showing one of the fingers or loop-holders. Fig. 7 is a partial section and elevation of the machine in line x^2-x^3 of Fig. 1. Fig. 8 is a top or plan view of one of the carriages to which the holders for the strand-carriers are attached. Fig. 9 is an enlarged detail, partially broken out, of one of 75 the holders with the strand-carrier omitted. Figs. 10 to 14, inclusive, are details showing the strand-carriers in different positions as they will appear in the manufacture of a plaited braid. Figs. 15 and 16 show a modified form of holder adapted for the reception of two strand-carriers; and Fig. 17 represents a modification of my invention, wherein two cores are shown with two extra needles.

80 Referring to the drawings, A represents a suitable bed-plate, it being herein shown as a cruciform. This bed-plate, as represented best in Fig. 7, has a hub A', which constitutes a bearing for the hub A² of the cam-plate A³, the said cam-plate having a cam-groove A⁴, 90 (see Fig. 1,) the said groove receiving a series of like rollers or other studs, as a, having plates a², connected, as will be described, each to a like slide b, to be herein described, the rotation of the said cam-plate causing the reciprocation of the plates and slides in a radial direction toward and from the center of the machine. As herein represented, the bed-plate has rising from it certain guideways A⁵, 95 there being in practice in the present ma- 100

chine four such guideways, each alike. These guideways in practice receive like slides b , and hence a full description of one set of devices made movable in one of the guideways 5 will suffice to enable all the like parts to be understood, and in the further description I will by like letters designate like parts, except as to the strand-carriers, which I shall letter separately to facilitate the description 10 of their movements.

I will now proceed to describe the devices shown in the guideway at the left-hand side of the drawings in Figs. 1 and 7. The guideway A^5 , shaped in cross-section, as shown in 15 Fig. 5, receives a slide b , the latter being kept down therein by means of suitable gibbs b' , attached thereto by suitable screws. The under side of each slide has, as herein shown, dovetailed projections, as b^2 , (see Figs. 2 and 20 3,) to receive between them the dovetailed plate a^2 referred to, the said plate being clamped at one edge (see Fig. 2) by means of a bolt, as b^3 , having an undercut notch with an inclined side, the said screw receiving upon 25 it a nut b^4 , which takes bearing upon a cross-rib of the carriage. The bolt b^3 serves to clamp the slide b firmly upon the plate a^2 in any desired position, so that the slide moves in unison with the plate, the adjustment of 30 the slide on the plate enabling the slide to terminate its forward or backward throw at any desired distance from the center of rotation of the cam-plate A^3 , that depending upon the kind of plait being laid.

35 To effect the adjustment of the slide b on the plate a^2 , I have provided the slide with a screw b^6 , having a head b^7 to bear against a rib of the slide, the screw rotating freely in the said rib without moving longitudinally, 40 the threaded part of the screw engaging a threaded stud b^8 , suitably attached to the plate a^2 , so that rotation of the screw b^6 draws the slide forward or backward upon the said plate.

45 Each carriage b , as herein shown, has near its inner end one or more studs or equivalents b^9 , which, as herein shown, are engaged by one or more springs, as b^{10} , attached to the carriage C , so that the said carriage may be 50 readily applied to or removed from the slide b , when desired. These carriages, as herein shown, consist, essentially, of a base, as c , having suitable uprights $c' c^2 c^3$, and having, preferably, a stud c^4 , which, as herein represented, serves merely as a rest upon which may be laid and held the needle-holder D , the said holder being retained upon the said carriage by means of a suitable screw, as c^5 , represented as screwed up through the base and 55 into the holder, as best shown in Figs. 7 and 9.

The holders D are suitably shaped to receive the like strand-carriers $e e' e^2 e^3$, to be carried by them as hereinafter described.

60 The holder D in the form in which I have herein represented the same has a guide-slot, as d , and a notch, as d^x , the carrier being normally kept pressed down in proper work-

ing position by a spring d^2 , attached at its rear end to the holder, as represented in Fig. 7. This holder, which may be of any suitable 70 or desired shape, is represented as containing bearings for a rock-shaft d^3 , carrying a clamping-lever d^4 , through which the strand 12 is led from a suitable spool f , the lower end of the said clamp, as herein shown, bearing upon the said braid 12, (see Fig. 4,) which is led from the said spool over a leader 18, and then through a suitable hole or eye at the upper end of the said clamping-lever. From the lower end of the clamping-lever d^4 the strand, 80 either flat braid or tape, or, it may be, a cord, passes over a take-up, (herein shown as a roll m at the lower ends of a lever m' ,) pivoted at 85 20 between the uprights $c^2 c^3$, the strand passing from the under side of said roll directly through the hollow strand-carrier or needle e . Each clamping-lever has a spring 24 connected to it by a rivet or screw 25, and the free end of the spring is acted upon by an adjusting-screw 26, the said spring normally acting to 90 keep the lower end of the clamping-lever on the strand passing between it and the upright part 27 of the holder.

As herein shown, the hollow strand-carriers or needles are alike, except as to size, they being shown of different sizes merely to represent their adaptation to strands of different width.

Each carrier, as herein represented, has a projection, as 22, which enters a notch d^x , 100 Fig. 9, in a part of the holder D , the said projection and notch constituting a kind of joint to permit the carrier or needle to rise and fall at its front end, the said carrier or needle between its ends passing through the suitable 105 slot d in a flange or upright d^{10} , forming part of the holder D , so that the said carrier or needle may rise and fall therein during the operation of plaiting, as will be described.

The carriers or needles $e e' e^2 e^3$, as herein 110 shown, are bent downwardly near their front ends at a little distance back from their points and are provided with suitable springs, as $h h' h^2 h^3$, the free end of each spring normally coming in contact with the under side 115 of the carrier or needle with which it co-operates, thus leaving a space between each carrier and the spring through which another carrier and the spring may pass when looping the strands together, the strand controlled by 120 a carrier resting against the spring of that carrier when the carrier is forward.

If desired, the holder D may be made in two pieces 30 31, as represented in Figs. 15 and 16; but this is only to enable the top part 125 31 to be changed for another top part in which the flange d^{10} contains two or more slots for two or more needles, for if one needle only is needed the holder may as well be made in one piece, as in Fig. 9.

130 By providing the flange d^{10} with more than one slot I may employ more than one needle in a carriage, as in Figs. 15 and 16, and when more than one needle is employed the holder

will also be provided with a suitable clamping-lever for each strand going to each needle.

- The take-up is acted upon by a suitable spring m^2 , (herein shown as attached at one end to the holder,) and merely to facilitate the connection of the said spring with the part m' of the take-up and enable the take-up to be actuated with greater or less power 5 I have connected a latch m^3 to one end of the spring, the said latch having several notches, (see Fig. 7,) and constituting an adjusting device for the said spring, the adjusting device being made to engage the 10 short arm of the take-up lever; but I desire it to be understood that the end of the said spring may be connected directly to the take-up lever or to any other usual form of adjusting device instead of the notched bar. 15 The bed A at one side has erected upon it, as herein shown, a suitable standard, as F, Fig. 7, provided with a suitable cross-arm F', having suitable pins or spindles, as F^2 , for the reception of suitable spools, as f, containing the strands 12 13 14 15 (see Figs. 10 to 12) 20 to be used in the plait, the several strands being led one to each one of the carriers or needles employed in the machine. One or all of the guideways are or may be provided 25 with spring-arms g, having cam-surfaces g^1 . I have shown these arms g on but two guideways—viz., those where the carriers e' and e^3 are used. These arms are secured by screws 30, and are acted upon through the forward 35 movement of a carriage by a suitable stud or projection, as g^2 , thereon, the stud being herein shown as attached to one of the uprights c^2 , the inner ends of the said arms having attached thereto suitable fingers, as g^4 , 40 Figs. 1 and 6, preferably attached thereto in an adjustable manner by screws g^5 , passing through slots in the said fingers, the said fingers being depressed at the proper times immediately above a strand to keep down the 45 "loop" or "stitch," as it may be called, of the braid delivered from the end of the carrier or needle immediately below it—as, for instance, the finger g^4 , shown in Figs. 11 and 12, keeps down the loop from the carrier or needle e' —the said finger preventing the rising 50 of the loop or stitch during the passage across it of one of the other carriers or needles, as will be described.
- The upper end of the hub A', Fig. 7, is 55 shown as provided with a post n, bent over at its upper end, which upper end has a suitable collar or head to receive a mandrel or core n' , the said core being held in adjusted position by a suitable screw n^2 . The plait to be made 60 is formed around the lower end of the mandrel or core and is fed off from the lower end thereof as made. This mandrel or core may be of any desired shape, and any desired number of mandrels or cores may be used, 65 according to the number of carriers or needles employed with each holder and the par-

ticular width or shape of the plaited braid to be produced.

In the drawings, Fig. 1, I have shown four needles, each provided with its own strand, 70 (herein supposed to be a flat tape or braid;) but I have not in said figure shown all the devices for actuating all the carriers or needles, because they are alike.

In operation, let it be assumed that each 75 strand-carrier or needle has been properly threaded, and that the ends of the strands have been connected together and are held by a suitable weight or other device, such as is commonly used in knitting or other machines, to put tension upon the said strands 80 while the machine is being started.

Referring to Figs. 1 and 10, they are supposed to show the carriers or needles in the 85 same position.

To facilitate the description of the operation I have designated the carriers or needles as $e e' e^2 e^3$ and the springs as $h h' h^2 h^3$, and the strands going to them as 12 13 14 15.

Referring to Figs. 1 and 10, the strand 13 90 has a stitch or loop formed about the carrier or needle e^2 , the carrier or needle e^3 has been pushed forward through between the carrier or needle e^2 and its spring h^2 and through a loop of the strand carried by the 95 carrier or needle e^2 , and the front end of the carrier or needle e^3 has been passed over the strand 12, carried by the carrier or needle e , which at that time is supposed to be fully retracted, a loop or stitch of the strand 12 100 being drawn about the strand 13. In Figs. 10 to 14 the mandrel or core n' is shown as occupying a position between the strands. The finger g^4 co-operates with the strand 13 to keep it down, and is in Fig. 10 shown as elevated above the said strand; but in Fig. 11 the said finger has been pushed down upon the said strand. With the strands in the position Fig. 10 the further rotation of the cam 105 A³ will cause the carriers or needles $e e' e^2 e^3$ 110 to be moved in the direction of the arrows thereon until they arrive in the position Fig. 11, wherein it will be seen that the carrier or needle e has moved forward and entered between the spring h^3 and the carrier or needle 115 e^3 , and in so doing has entered a loop or stitch of the strand 15, and that the carrier or needle e' has been moved slightly back, while the carrier or needle e^2 withdraws out from 120 the loop or stitch in the strand 13, the movement of the carrier or needle e' being sufficient to cause it to draw the strand 13 about the strand 14, as represented in Fig. 11, and the finger g^4 comes down upon the strand 13, 125 so that when the carrier or needle e is again moved forward its point will cross the strand 13. A third position of the carriers or needles is shown in Fig. 12, wherein it will be seen that the carrier or needle e has been pushed 130 fully through the loop or stitch in the strand 15 of the carrier or needle e^3 , and that the

- carrier or needle e' has been pushed forward through a loop of strand 12, carried by the carrier or needle e , and in the passage of the carrier or needle e' between the carrier or needle e and the spring h the point of the said carrier or needle passes over the strand 14. Continuing this operation, the carriers or needles e and e^2 and e' and e^3 are made to work in pairs, the needles of each pair moving in the same direction in substantially the same time, that needle of the pair which is being retracted being started first by the cam-groove, the other needle of the pair following it and continuing to move slightly after the 15 needle stops. In this way it results that a series of stitches or loops are formed in the strands, one loop locking the other and forming a plaited braid substantially such as represented in Fig. 12, wherein it will be seen that the loops are laid at angles to each other, and that the resultant braid is rectangular in cross-section.
- It will be obvious that the cross-sectional shape of the plaited braid may be made to 25 vary—that is, it may be quadrangular, quadrilateral, or triangular—according to the number and location of the carriers or needles and their angular position with relation to each other.
- 30 Figs. 13 and 14 show how the strands are bent backward and forward in regular layers from end to end of the plaited braid, and in this way the strand is not twisted, so it becomes possible to plait narrow braids or tapes 35 into a larger plaited braid without twisting any of the strands.

The carriers or needles in their operation are made to cross each other at an angle and form their strands into loops to be entered by 40 other strands delivered by other carriers or needles.

In the manufacture of the plaited braid herein shown it will be understood that one loop is formed after another in the direction 45 of the length of the braid, and as there are four carriers the loops are really laid or superimposed in succession, one at each of the four sides of the braid, the formation of the loops or stitches following loop after loop 50 about the four sides of the braid.

In the production by machinery of braids other than flat it is customary to move the strand-carriers around a center, some carriers moving in one and others in an opposite direction, the strands taking a spiral direction 55 in the article produced, as in braiding-machines.

In this my invention the carriers have only a movement of reciprocation in a right line, 60 and the strand delivered by each carrier appears as if corrugated, or layer after layer in the same strand appears superimposed, one layer over another, the said layers being connected by cross-layers formed of other strands.

65 Prior to my invention strands of thread, &c., carried by needles have been looped together, as in sewing-machines; but prior to

my invention I am not aware that three or more strand-carriers have ever been provided with strands and made to cross each other in 70 an angular direction to interloop loops of the said strands together and produce a plaited braid.

I do not desire to limit my invention to the exact shape shown for the strand-carriers, nor 75 to the exact devices by which to reciprocate the same so as to cross each other in angular direction, as the devices for reciprocating the said carriers might be variously modified without departing from my invention. 80

By the term "series of strand-carriers" I mean more than two such carriers.

In Fig. 17 I have shown a modification wherein I have represented an extra core or mandrel, marked n'^x , extra needles e'^x and e^{3x} being added, the said figure showing the concatenation of the braid and suitable needles, that the braid is wider than it is thick, and that the cores or mandrels are bent in slightly toward each other at their lower 90 ends.

I claim—

1. An organized machine for the manufacture of plaited braid, it containing three or more reciprocating strand-carriers arranged 95 at an angle to each other and crossing each other in their reciprocations, each strand-carrier entering a loop made in the strand carried by another carrier, and in turn having a loop made in its own strand entered by a 100 loop of a strand carried by another carrier, substantially as described.

2. A series of strand-carriers having attached springs and a series of holders to which the said carriers are attached, combined with means to reciprocate the said holders and strand-carriers, the latter crossing each other at an angle, substantially as described. 105

3. A series of strand-carriers having attached springs and a series of holders to which the said carriers are attached, combined with a mandrel and means to reciprocate the said holders and strand-carriers, the latter crossing each other at an angle, substantially as described. 110

4. A series of strand-carriers, holders to which they are attached, strand-clamping devices, and take-up devices, combined with means to reciprocate the said holders and 115 cause the said strand-carriers to cross each other at an angle to interloop their strands, substantially as described.

5. A series of strand-carriers, a series of holders to which they are attached, a take-up 125 for the strand carried by each carrier, a series of carriages to which the said holders are attached, a series of slides to which the carriages are attached, and means to reciprocate the said slides, substantially as described. 130

6. The cam-disk A^3 , the series of plates actuated thereby, and a series of slides b , combined with adjusting devices, substantially as described, to adjust the said slides

toward or from the center of the said cam-disk.

7. A series of longitudinally-reciprocating strand-carriers and a mandrel or core, combined with fingers to keep down the loops of the strands, substantially as described.

8. The herein-described method of forming plaited braid from three or more strands, which consists in forming loops in the said 10 strands in succession and locking the said

loops in succession around or at the different sides of the braid each by a loop of another strand, as set forth.

In testimony whereof I have signed my name to this specification in the presence of 15 two subscribing witnesses.

ANALDO M. ENGLISH.
